UNITED STATES PATENT OFFICE.

WILLIS A. BARNES, OF NEW YORK, N. Y.

CARRIAGE FOR MAIL-BAGS.

SPECIFICATION forming part of Letters Patent No. 245,119, dated August 2, 1881.

Application filed May 21, 1881. (No model.)

To all whom it may concern:

Be it known that I, WILLIS A. BARNES, a citizen of the United States, residing at New York, in the county and State of New York, 5 have invented new and useful Improvements in Carriages for Mail-Bags, &c., of which the following is a specification.

The primary object of my invention is to produce a wheeled hand - vehicle for carrying 10 the bag used in collecting mail - matter from lamp - post boxes and other places, or for carrying articles of merchandise, which shall be light in its construction, easily propelled, and adapted to fold into a small compass.

15 My invention is illustrated in the accompanying drawings, in which—

Figure 1 represents a side elevation. Fig. 2 is a plan or top view. Fig. 3 is a detail view of the catch. Fig. 4 is a like view of the 20 hooks.

Similar letters indicate corresponding parts.

The letter A designates a reach, the forward 25 end of which is connected to the main wheel B, and which, together with a frame C, constitutes the body of the vehicle. The frame C carries the hind wheels, D, two in number, at its lower end, and it is connected to the reach A at its upper end by a pivot, 5.

From the reach A to an intermediate portion 30 of the hind - wheel frame, B, extends a brace, E, which has a pivotal connection with both the reach and frame, and is jointed about midway of its length, as at 6. The reach A extends rearward beyond the point of its connection with the frame C, and on the rear end thereof is arranged an extensible push-handle, 35 F, which is preferably curved lengthwise, and which, in this example, slides through an eye, 7, fixed to the reach, while it is provided with a similar eye, 8, embracing and sliding on the 40 reach. The arrangement of this handle, however, is subject to modifications which will readily suggest themselves to a skilled mechanician. The letter G designates a catch 45 hinged to the reach, as at 10, and H designates hooks fixed to the reach at its opposite sides.

When the hind - wheel frame C is thrown 50 back on its pivot 5 away from the main wheel, and the brace E is extended, the parts are retained in the proper relative positions to allow the vehicle to be propelled by taking hold

of the push-handle F, while, if the brace is folded on its joint 6, the hind-wheel frame can be swung toward and brought under the reach, 55 thus bringing the whole into a small compass or area, which can be further reduced by sliding the handle inward upon the reach. The principal object of the sliding or extensible handle, however, is to accommodate the vehicle to different persons, as to a man or a boy, and by curving the handle it can be varied not only in length, but also in its height from the ground.

When the carriage is used for collecting 65 mail-matter the mail-bags are simply hung on the hooks H, one for letters and the other for newspapers, &c., and in that event the catch is bifurcated, as at 11, so that it is adapted to engage a lamp-post, and thus hold the vehicle 70 in place during the time the mail-matter is being taken from the lamp-post box and deposited in the bags. The importance of this catch will be better understood when it is considered that a large number of the collectors of mail- 75 matter are selected from those persons having but one arm, which, of course, is left free when the catch is brought into use; and also that the streets often deviate from a level surface to an inclined plane, making it necessary to 80 check the vehicle.

When the carriage is used for collecting or 85 delivering articles of merchandise—as, for example, packages of dry-goods—the catch may be constructed to be locked to a railing, grating, or other place on either side of the vehicle, and in that case, moreover, a latch or lock or other similar device may be substituted for the hooks H for securing to the article a box or other receptacle.

90 The hind wheels, D, are fixed to independent axles 12, having their bearings I connected to the base part of the frame C by swivel-joints 13. By this arrangement of the bearings I the hind wheels, D, are allowed to follow the 95 track or course of the main wheel B; or, in other words, they are not liable to steer or throw the carriage out of its course, which is the case when the hind wheels of a carriage are placed on a common axle having fixed 100 bearings.

What I claim as new, and desire to secure by Letters Patent, is—

1. The combination, substantially as here-

inbefore set forth, of the reach having its forward end connected to the main wheel, the hind-wheel frame having a pivotal connection with the reach, and the folding-brace extending from the reach to the frame.

2. The combination, substantially as hereinbefore set forth, of the reach having its forward end connected to the main wheel, the extensible push-handle arranged on the rear end 10 of the reach, the hind - wheel frame having a pivotal connection with the reach and the folding-brace extending from the reach to the frame.

3. The combination, substantially as hereinbefore set forth, of the reach having its forward end connected to the main wheel, the 15

catch hinged to the reach, the hind - wheel frame, and the brace.

4. The combination, substantially as hereinbefore set forth, of the reach having its forward end connected to the main wheel, the hooks or their substitutes fixed to the reach on opposite sides thereof, the hind-wheel frame, and the brace.

In testimony whereof I have hereunto set 25 my hand and seal in the presence of two subscribing witnesses.

WILLIS A. BARNES. [L. S.]
